UNITED STATES PATENT OFFICE.

CARL E. BAUER, OF HAMMOND, INDIANA, ASSIGNOR TO SIMPLEX RAILWAY APPLIANCE COMPANY, OF CHICAGO, ILLINOIS, A CORPORATION OF ILLINOIS.

REVERSIBLE FULCRUM.

No. 840,740.

Specification of Letters Patent.

Patented Jan. 8, 1907.

Application filed May 9, 1906. Serial No. 315,886.

To all whom it may concern:

Be it known that I, CARL E. BAUER, a citizen of the United States, residing at Hammond, in the county of Lake and State of Indiana, have invented certain new and useful Improvements in Reversible Fulcrums, of which the following is a specification.

The invention relates to reversible fulcrums for brake beams, and particularly to those brake beams which are provided with a truss. The invention has for its objects to provide a reversible fulcrum arranged to be positively stopped or positioned in its two limits of movement; to provide a fulcrum which may be secured to the trussed beam without having to slip the holding clip over the end of the beam; to provide a fulcrum in which the head of the king post constitutes the stop for governing its position rotatively; and finally to provide an effective durable fulcrum of comparatively inexpensive construction. These and other objects are accomplished by my construction which is illustrated in one form in the accompanying drawings in which

Figure 1 is a plan view showing the trussed brake beam with the fulcrum thereon;

Figure 2 is a perspective view of the fulcrum;

Figure 3 is a longitudinal section through the fulcrum shown in Figure 2, on the line III-III;

Figure 4 is a transverse section through the fulcrum on the line IV-IV of Figure 3; and

Figure 5 is a transverse section through the fulcrum of Figure 2 on the line V-V.

As shown in the drawings A is the brake beam which may be of any preferred design but is preferably a U shaped commercial section as indicated by the cross section in Figure 3, B is the truss for the beam which in the present instance is round but which may be of any desired cross section, and C is the fulcrum which is designed to be rotatably supported on the brake beam and truss whereby it may be used either lefthanded or righthanded. The central portion of the revoluble king post 6 is split intermediate its ends as in the ordinary type of fulcrums, and is provided with the hole 7 for the pivot

bolt. The upper end of the king post 6 is secured to the brake beam A by means of the open sided clip 8 which clip as indicated in Figures 2 and 3, encircles the beam and is secured by the through holding means or bolts 9. The lower inside edges of the clip 8 are provided with projecting portions 10 which portions are adapted to support the bushing 11. The bushing 11 is divided centrally as indicated in Figure 4 and forms a supporting member for the head 12 of the king post, thereby supporting it revolubly. The bushing is held in position by means of the through-bolts 9 which also secure the clip 8 in place. It will be seen that by using an open sided clip I am enabled to apply the fulcrum to the beam without slipping the clip over the end of the beam, as such clip can be placed over the top of the beam, and the bushing 11 engaging the head of the king bolt slipped in endwise and all secured together by means of the bolts 9. It will be seen that the parts are very easily assembled and when positioned a very secure fastening is provided for the upper end of the king bolt. As the device is designed to be reversible and the king bolt must occupy positions at an angle of about 80° to each other, such bolt is mounted revolubly at top and bottom and in order to positively position the king bolt in either of these two positions I construct my head in such a way that it will stop the rotation of the king bolt when it has arrived at either one of these two positions. This construction is clearly shown in Figure 4, in which it will be seen that the head 12 is in effect a pointed oval, and that in the position shown in Figure 4 the points of the oval take against the sides of the beam A and positively position the king bolt. It will be seen that a motion of about 80° in a clock-wise direction will bring the points in engagement with other portions of the beam thereby giving the reverse position of the fulcrum. It will be seen that this constitutes a very simple and efficient means for positioning the king bolt and that no extra or additional stops need be provided for this purpose. The lower portion of the king bolt 6 is supported in the member 13 which member is provided

with an upstanding portion 14 engaging the central part of the king bolt while the bottom portion thereof is recessed to receive the truss B as clearly indicated in Figure 3. The 5 supporting part 13 is prevented from rotation by reason of its engagement with the truss B and is provided with a stop for assisting in the positioning of the king bolt as indicated in Figure 5. This stop consists of 10 an upstanding flange 14 on the member 13 which flange is adapted to contact with the parts 15 on the lower end of the king bolt. These stops correspond in position with the 15 stops on the upper end of the king bolt and the king bolt is thus positively positioned not only at the top but also at the bottom. The member 13 is provided with the usual 20 perforated lug 16 to afford a seat for the bolt to which a safety chain is attached to support the brake beam. It will be seen from the foregoing that my construction is a very cheap and inexpensive one and one that may be applied expeditiously to the beam without any necessity of slipping the holding clip 25 over the end of the beam. It will be seen furthermore that the king post is positively positioned both top and bottom in a simple yet very effective manner without the necessity of supplying additional stops and 30 ceases.

It will be apparent that the invention is capable of considerable modification without departing from the spirit thereof. The beam is not necessarily U shaped and in fact 35 might be some other shape or rectangular and if desired the pointed oval head of the king post might take against the sides of the clip instead of the sides of the beam. It will also be apparent that the head of the king 40 post might be of a shape other than a pointed oval as other shapes might be used wherein the shape of the head was such that it would be stopped against the sides of the U shaped member at the desired points. My invention comprehends these and other modifications which will be apparent to those skilled 45 in the art, and are within the scope of the invention.

Having thus described my invention and 50 illustrated its use, what I claim as new, and desire to secure by Letters Patent, is the following:

1. In combination with a brake beam, a fulcrum comprising an open sided clip adapted to fit over the beam and provided with projecting inner edges, a headed king post adapted to fit such clip and securing means interposed between the said inner edges and the head of the king post.
2. In combination with a brake beam, a fulcrum comprising an open-sided clip adapted to fit over the beam and provided with projecting inner edges, a headed king post adapted to revolvably fit such clip and secur-

ing means interposed between the said inner 65 edges and the head of the king post.

3. In combination with a brake beam, a fulcrum comprising an open sided clip adapted to fit over the beam and provided with projecting inner edges, a headed king post 70 adapted to fit such clip, securing means interposed between the said inner edges and the head of the king post, and through holding means to secure the clip to the beam and hold the said securing means in place. 75

4. In combination, a supporting means U shaped in section, a king post provided with a head fitting the supporting means, which head is shaped to be partially revoluble in the supporting means but to be positively stopped 80 at a certain point, by the engagement of the head with the sides of the supporting means, and means for securing the head against longitudinal movement in the supporting means.

5. In combination, a supporting means U 85 shaped in cross section, a king post provided with a head engaging the supporting means, which head has a short diameter fitting the inside width of the supporting means and a long diameter whereby the post will be positively stopped after a certain amount of revolution, and means for securing the head against longitudinal movement in the supporting means.

6. In combination, a supporting means U 95 shaped in cross section, a king post provided with a head fitting the supporting means, which head is a pointed oval with the short diameter approximately fitting the inside width of the supporting means, and means 100 for securing the head in the supporting means against longitudinal movement.

7. In combination with a trussed brake beam, an open sided clip for the beam provided with inner projecting edges, a king 105 post supporting member having an open sided recess to engage the truss, a king post provided with a head engaging the clip and a bottom portion engaging the supporting member, and holding means interposed between the projecting edges of the clip and the head of the king post. 110

8. In combination with a trussed brake beam, an open sided clip for the beam provided with inner projecting edges, a king 115 post supporting member having an open sided recess to engage the truss, a king post provided with a head rotatably engaging the clip and a bottom portion engaging the supporting member, and holding means interposed 120 between the projecting edges of the clip and the head of the king post.

9. In combination, a brake beam U shaped in cross section, an open sided clip therefor, and a king post revolvably supported therein 125 and provided with a head having stops adapted to engage the sides of the beam and limit the movement of revolution.

10. In combination, a brake beam U shaped in cross section, an open sided clip therefor, and a king post revolubly supported therein and provided with a pointed oval head
5 adapted in certain positions to be positively engaged by the sides of the beam whereby the post is positioned rotatively.

In testimony whereof I have hereunto signed my name in the presence of the two subscribed witnesses.

CARL E. BAUER.
